UNITED STATES PATENT OFFICE

164,094

WALL SHELF

Carl F. Bollmeier, Milwaukee, Wis.

Application September 26, 1949, Serial No. 5,173

Term of patent 7 years

(Cl. D33—3)

To all whom it may concern:

Be it known that I, Carl F. Bollmeier, a citizen of the United States, residing at Milwaukee, in the county of Milwaukee and State of Wisconsin, have invented a new, original, and ornamental Design for a Wall Shelf, of which the following is a specification, reference being had to the accompanying drawing, forming part thereof.

Fig. 1 is a view in perspective of a wall shelf embodying my new design.

Fig. 2 is a view taken in section through the wall shelf shown in Fig. 1.

Fig. 3 is a fragmentary detail view in section on the line 3—3 of Fig. 1.

I claim:

The ornamental design for a wall shelf, as shown.

CARL F. BOLLMEIER.
